(57) **CLAIM**

The ornamental design for a combined printer and scanner, as shown and described.

DESCRIPTION

FIG. 1 is an enlarged perspective view of the top, front and right side of a combined printer and scanner showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another enlarged perspective view with the screen in a raised position and paper output tray in the extended position.

1 Claim, 6 Drawing Sheets
